UNITED STATES PATENT OFFICE.

DANIEL LOUIS LUDDINGTON, OF GRASS VALLEY, CALIFORNIA, ASSIGNOR
OF ONE-HALF TO GEORGE MAINHART, OF GRASS VALLEY, CALIFORNIA.

EXTENSION-BIT OR DRILLING-TOOL.

SPECIFICATION forming part of Letters Patent No. 744,925, dated November 24, 1903.

Application filed August 3, 1903. Serial No. 168,029. (No model.)

To all whom it may concern:

Be it known that I, DANIEL LOUIS LUDDINGTON, a citizen of the United States, residing at Grass Valley, in the county of Nevada and

5 State of California, have invented new and useful Improvements in Extension-Bits or Drilling-Tools, of which the following is a specification.

This invention has relation to improvements in drilling-tools; and it consists in the novel construction, combination, and arrangement of parts of which it is composed, whereby the bit is extensible while the process of drilling is carried out, all as will be herein-after more fully explained, and particularly pointed out in the appended claim.

The annexed drawings, to which reference is made, fully illustrate my invention, in which—

20 Figure 1 represents a side view of my improved drilling-tool. Fig. 2 is a vertical longitudinal sectional view of the same, and Fig. 3 represents a transverse vertical sectional view.

25 Referring by letter to the accompanying drawings, A designates the hand drilling-tool, comprising the body portion or handle a, which is provided with a central opening b to receive the stem c of the bit-holder d, which 30 latter is hollow, providing a central passage e for the bit, and the same is constructed with an enlarged portion f, having a shoulder g, adjacent to which is a pinion h, arranged upon the narrow stem of the holder. Se- 35 cured to the handle is a spring-arm i, pro- 40 vided with a notch or cut-away portion j op- 45 posite to the pinion, and the end thereof has an opening k, in which is seated a key or wear- 50 pin l, that is designed to hold the pinion in place. This spring-arm i will yield when the notched end thereof is raised to permit the pinion h to pass the inner end of the pin l in detaching the bit-holder d from the body or handle a or attaching the same to said han- 55 dle. The bit after insertion into the hollow holder and adjusted in position is held in place by a set-screw m on the holder.

B represents a bar, which is provided with teeth n, that engage the teeth of the pinion, and the same is provided with a handle o, by 50 which said toothed bar is operated.

Having thus described the various parts of which my device is composed, I will now explain its operation. The bit being adjusted within the hollow holder and the toothed bar 55 arranged within the cut-away portion and engaging the pinion, the operator grasps the handle of the toothed bar and draws and forces the same back and forth, which causes the pinion to revolve first in one direction and then another direction, thereby reversing the revolution of said pinion with every stroke of the toothed bar, thus imparting such movement to the bit in drilling. A string or wire p is connected to the inner end of the bit and serves 60 to bring the bit forward in adjusting the same, and the notch or cut-away portion in the end of the spring-arm serves as a guide to the toothed bar in its movements.

It will be seen that the wear-pin l being de- 70 tachable the same can be withdrawn when worn and replaced by another.

I do not wish to be confined to the exact construction of my device, as various changes may be made in its construction without de- 75 parting from the spirit of my invention.

What I claim as new, and desire to secure by Letters Patent, is—

The combination with the bit, hollow holder and handle, said holder provided with the 80 pinion, of the toothed bar and spring-arm, the latter provided with the notch adjacent to said pinion, and the pin inserted in the end of said arm and adapted to hold the pinion in position, as shown and described. 85

In testimony whereof I have signed my name to this specification in the presence of two subscribing witnesses.

DANIEL LOUIS LUDDINGTON.
